UNITED STATES PATENT OFFICE

2,001,540

EVAPORATOR FOR REFRIGERATING SYSTEMS

Delbert F. Newman, Schenectady, N. Y., assignor to General Electric Company, a corporation of New York

Application July 1, 1933, Serial No. 678,628

3 Claims. (Cl. 62—95)

My invention relates to evaporators for refrigerating systems.

Evaporators for refrigerating systems are commonly provided with space for accommodating freezing trays wherein water or desserts may be frozen. It is often desirable to provide a refrigerated shelf within this compartment in order that additional freezing trays may be placed therein.

10 Accordingly it is an object of my invention to provide an evaporator having a refrigerated shelf of high heat-absorbing capacity and which shall be of a simple and rugged construction.

Further objects and advantages of my invention will become apparent as the following description proceeds, and the features of novelty which characterize my invention will be pointed out with particularity in the claims annexed to and forming a part of this specification.

20 For a better understanding of my invention reference may be had to the accompanying drawing in which Fig. 1 is an elevation partly in section of a refrigerating machine provided with a cooling unit embodying my invention, and Fig. 2 is a detail perspective view, partly in section, of the cooling unit shown in Fig. 1.

Referring to Fig. 1, I have shown a refrigerating machine including a compressor and condenser unit comprising a compressor casing 10 and a condenser 11 mounted on a removable top 12 of a refrigerating cabinet 13. Within the cabinet and suspended from the top 12 is an evaporator 14 embodying my invention. In this machine gaseous refrigerant is compressed by a motor-driven compressor within the casing 10 and passes into the condenser 11 where it is liquefied and flows to a flow-control device 15 from which it passes in regulated quantities through a conduit 16 to a conduit within a shelf 17 of the evaporator. The evaporator 14 is of the flooded type and comprises a depending U-shaped portion 18 having headers 19 and 20 formed at the upper ends thereof and connected by a tube 21. The shelf 17 is secured to the side walls 22 of the depending portion 18. Liquid refrigerant passing through the conduit within the shelf 17 flows up to the header 19 through a conduit 23, and refrigerant vaporized by the absorption of heat within the conduit in the shelf 40 is forced out to the header 19 with the flow of the liquid refrigerant. The U-shaped portion 18 is filled with liquid refrigerant, which partially fills the headers 19 and 20 to the level indicated at 20a in the header 20. Upon absorbing heat, the 50 liquid refrigerant vaporizes and the vaporized

refrigerant is withdrawn from the evaporator 14 by a conduit 24 connecting the header 19 and the intake of the compressor within the casing 10.

The construction of the evaporator 14 is clearly shown in Fig. 2, which is a perspective view from the rear of the evaporator. The U-shaped portion 18 and the headers 19 and 20 are formed of inner and outer shells 25 and 26 respectively, having horizontal indentations forming the headers 19 and 20. The shell 26 is provided with 10 indentations or corrugations 27 at right angles to the headers and forming refrigerant-circulating passages communicating with the headers at opposite ends of the passages. The edges of the shells 25 and 26 are secured together by folding 15 the edge of the shell 25 over the edge of the shell 26 and by welding or otherwise sealing the joint formed, and the corrugations in the shell 26 are also joined by the shell 25 to resist internal pressure. The shelf 17 in the embodiment illustrated 20 comprises a sinuous conduit 28 about which is cast a body of metal 29 of high thermal conductivity such as aluminum. Lugs 30 are provided at the sides of the shelf 17 for securing it by screws 31 to the depending walls 22. The 25 conduit 28 communicates with the header 19 at the rear of the cooling unit through the conduit 23, which is a continuation of conduit 28. At the other side of the shelf, the conduit 28 is connected to the conduit 16 through which refrigerant is admitted thereto.

In the operation of the refrigerating system shown, refrigerant is compressed in the casing 10, liquefied in the condenser 11, and admitted to the conduit 16 in regulated quantities by the flow control device 15. Liquid refrigerant passes from the conduit 16 to the conduit 28 and absorbs heat from the shelf and articles resting thereon. Any gas which is formed during this absorption of heat will be forced out with the flow of liquid and 40 will not remain to form an insulating layer, which would reduce the heat-absorbing capacity of the evaporator shelf. Refrigerant after passing through the shelf 17 will flow upward through the conduit 23 to the header 19. The level of liquid refrigerant in the cooling unit is maintained 45 in both of the headers 19 and 20 about as shown at 20a in Fig. 2. The indentations of the U-shaped portion 18 are thus maintained filled with liquid refrigerant, and any gas formed by the absorption of heat from the chamber to be cooled or from freezing trays placed on the bottom of the U-shaped portion 18 will rise to the headers 19 and 20, and will be withdrawn from the header 50 through the conduit 24 which is connected to the 55

intake port of the compressor within the casing 10. The tube 21 is provided to permit ready passage of gaseous refrigerant between the headers 19 and 20 and thus equalize the pressures therein so as to facilitate the circulation of liquid refrigerant in the evaporator.

An evaporator constructed in accordance with my invention is highly efficient, as has been pointed out, since gaseous refrigerant cannot remain 10 in the shelf to reduce the absorption of heat by the shelf. The manufacture of the evaporator described herein is simple since the main body of the evaporator may be constructed of sheet metal, and the shelf easily attached thereto.

15 Although I have shown and described my invention in connection with a compression refrigerating machine, it will be apparent that it is applicable to other uses, and I do not desire my invention to be limited to the particular construction shown and described, and I intend in the appended claims to cover all modifications within 20 the spirit and scope of my invention.

What I claim as new and desire to secure by Letters Patent of the United States is:

25 1. A refrigerating system including a flooded evaporator having a header and a depending refrigerant-circulating portion, a cast metal shelf secured to said depending portion and having a refrigerant conduit embedded therein, means for

circulating liquid refrigerant through said conduit and for then supplying said liquid refrigerant to said evaporator, and means for withdrawing gaseous refrigerant from said header.

2. A cooling unit for refrigerating machines including an evaporator comprising a U-shaped refrigerant-circulating portion and a header at each end of said portion, means for providing communication between said headers, a shelf secured between the sides of said U-shaped portion, a refrigerant conduit connected to said shelf in heat exchange relation therewith, means for admitting refrigerant to said conduit, means providing communication between said conduit and said evaporator, and means for withdrawing refrigerant from one of said headers. 5 10 15

3. A cooling unit for refrigerating machines including an evaporator comprising a U-shaped refrigerant-circulating portion and a header at each end of said portion, means for providing communication between said headers, a shelf secured between the sides of said U-shaped portion, a sinuous conduit embedded in said shelf, means for admitting refrigerant to said conduit, means providing communication between said conduit 20 and said evaporator, and means for withdrawing refrigerant from one of said headers. 25

DELBERT F. NEWMAN.
